United States Patent Office.

CALVIN A. LEONARD, OF ROCHESTER, NEW YORK.

Letters Patent No. 98,170, dated December 21, 1869.

IMPROVEMENT IN INSOLES FOR BOOTS AND SHOES.

The Schedule referred to in these Letters Patent and making part of the same

To all whom it may concern :

Be it known that I, CALVIN A. LEONARD, of the city of Rochester, in the State of New York, have invented certain new and useful Improvements in Insoles; and I do hereby declare that the following is a full, clear, and exact description thereof, reference being had to the accompanying drawings, making part of this specification, in which—

Figure 1 is a face view of an insole, with my improvement attached ;

Figure 2 is an obverse view ; and

Figure 3 is a longitudinal section.

The object and nature of my invention will be understood by reference to the specification and drawings, and to enable others to make and use the same, I will describe its construction.

It is well known that a great objection to the ordinary insole is its liability to break and curl in the shank, chiefly because of the decreased width at this point, and the softening of the stiffening by moisture from the foot.

To obviate this difficulty, I provide a strip of sheet-metal, *a*, figs. 1 and 3, upon one or both sides of the stiffened body *A* of the insole, located longitudinally with the same, directly at the shank. This strip may be of any desirable length, to suit different sizes of insoles, and is secured to the insole by binding over the ends and tucking them through slits cut transversely

in the body *A*, after which the ends may be pressed close against the material upon the opposite side, as shown in figs. 2 and 3.

This arrangement prevents the curling or breaking of the insole, which often occurs when the foot is withdrawn from the boot or shoe, and the insole is moist or soft.

It is obvious that my invention is applicable to any kind of insole, whether composed of one or more thicknesses of material, and the strips *a* may be arranged upon the same side of the stiffening as the felt or other material of which the insole is composed, as shown in fig. 3, or upon the opposite side, since the thickness of the strip is so slight as not to interfere in any way with the comfort of the wearer, even when worn next the foot.

It also possesses the advantages of cheapness and simplicity of construction, and it easily conforms to the shape of the boot or shoe in which it is worn.

What I claim as my invention, and desire to secure by Letters Patent, is—

The metallic stiffener *a*, of removable insoles, when its attachment thereto is effected by means of projecting points at the ends, as shown and described.

C. A. LEONARD.
